DESIGN FOR A BOOT

Gus E. Bergman, Columbus, Nebr.

Application June 18, 1941, Serial No. 101,523

Term of patent 14 years

To all whom it may concern:

Be it known that I, Gus E. Bergman, a citizen of the United States, residing at Columbus, County of Platte, and State of Nebraska, have invented a new, original, and ornamental Design for a Boot, of which the following is a specification, reference being had to the accompanying drawing forming a part thereof, in which:

Figure 1 is a perspective view of a boot, showing my new design; Fig. 2, a rear elevational view; and Fig. 3, a plan view of the same.

I claim:

The ornamental design for a boot, as shown.

GUS E. BERGMAN.
